VIBRATORY CONVEYER WITH DEFORMABLE DRIVE COUPLING

Robert M. Carrier, Jr., Aurora, Ill., and Maurice G. Whitley, Louisville, Ky., assignors, by mesne assignments, to Carrier Conveyor Corporation, Louisville, Ky., a corporation of Kentucky

Application February 28, 1948, Serial No. 11,998

7 Claims. (Cl. 198—220)

1

This invention relates to improved conveyor apparatus and to drive means and more particularly has to do with spring-mounted conveyors, the drive mechanism of which is automatically synchronized with the natural frequency of the spring mounting to obtain motivation of the conveyor with minimum power consumption. The resonant drive mechanism of this invention is particularly advantageously applied to a conveyor which moves material along the conveying surface due to a reciprocating and oscillating movement, or a similar movement, of the conveyor itself.

Heretofore, low frequency spring mountings have been provided for conveyors to resiliently support the conveyors and to absorb vibrations during operation. However, due to the fact that the natural frequencies of the springs in these mountings were low compared to the frequency of operation of the conveyor, the conveyor drive means in effect acted against the vibrating action of the spring at various times during the operation.

This phenomenon can best be explained by visualizing a large coil spring suspended from an overhead upright on a support. If a piece of material, for example, a 100 pound block of steel, were secured on the lower end of the coil, a person could cause the 100 pound block to move up and down over a limited range merely by pushing down periodically on the block secured to the spring. If the pushes are not synchronized with the coiling and uncoiling of the spring, much power will be wasted when applied against the action of the spring. However, if the pushes are synchronized with the natural vibrating frequency of the spring, pushes having only a fraction of the power of the unsynchronized pushes, will be sufficient to keep the 100 pound block moving up and down with the coils.

According to the principles of our invention, a conveyor, such as a spring mounted spiral or trough conveyor, moving material along the conveying surface by the directional throw principle, is provided with a drive mechanism that operates the conveyor at a frequency substantially in resonance with the natural frequency of the spring mounting. It has been found that by synchronizing the operation of the conveyor with the natural frequency of the spring mounting, a saving in the order of 90% in power consumption can be thereby attained.

It is therefore an object of this invention to provide means for driving a spring mounted load at a speed in resonance with the natural frequency of the spring mounting.

A further object of this invention is to provide a spring mounting for a spiral conveyor which not only resiliently supports the conveyor

2

but also acts to center it about an imaginary center axis.

Still another object of this invention is to provide a method of causing material to convey up a spiral or on a trough using the principle of natural frequency.

A particular feature of this invention resides in the provision of a constant speed motor selected to operate the conveyor at the natural frequency of the spring mounting.

A further feature of this invention is the provision of a spring mounting comprising spring arms made of spring stock which are positively fixed to the periphery of the conveyor and to a base member for performing the three-fold function of acting as the central bearing member for the conveyor, supporting the conveyor, and oscillating the conveyor about an imaginary vertical axis.

Another and still further feature of this invention is the provision of a fluid drive means which permits the conveyor to automatically adjust the length of the drive arm so that the weight of the conveyor will rest on the spring mounting regardless of the load on the conveyor.

The novel features which we believe to be characteristic of our invention are set forth in the appended claims. Our invention, however, both as to its manner of construction and method of operation, together with further objects and advantages thereof, may best be understood by reference to the following description, taken in connection with the accompanying drawings, in which:

Figure 1 is a fragmentary front elevational view of a spiral conveyor constructed according to the teachings of our invention;

Figure 2 is a fragmentary side elevational view, partly in section, of the spiral conveyor of Figure 1;

Figure 12 is a more or less diagrammatic showing of a modified drive mechanism applicable to the conveyor of Figure 8; and

Figure 13 is a view similar to Figure 12 showing a modified drive mechanism applicable to the conveyor of Figure 8.

As shown on the drawings:

The embodiment of the present invention disclosed in Figures 1 and 2 comprises a frame support structure 10 in which a helical conveying flight 11 is supported for oscillation about a substantially vertical shaft 12 and for reciprocation in a vertical direction relative to the frame structure.

The conveyor is arranged to move material up the flight by using the directional throw principle of conveying. This method of conveying, when applied to a helical conveyor, requires that the helical flight be oscillated about its center axis at the same time that it is being reciprocated in a vertical direction. Thus, each point on the conveyor flight is first given a twisting, upwardly movement at a fixed angle to the angle of climb of the flight. If, for example, the angle of climb of the conveying flight is 10° with the horizontal, the flight may be twisted upwardly at an angle of, for example, 45° to the horizontal. Then, when the movement of the flight is reversed and it is twisted downwardly, the material on the flight will be thrown forwardly off the flight at an angle approximately 35° thereto and will come to rest on an advanced part of the conveyor due to the fact that it has been thrown forwardly and also due to the fact that the flight has been moved backwardly while the material is out of contact with the surface of the flight.

The frame structure 10 comprises a base 15 supported in spaced relation to the floor by foot members 16 disposed at each corner of the base. A pair of vertical angle members 17 and 18 are secured, as by welding, at each side of the base 15. These angle members are spaced from each other and carry between them a curved guide plate 20 having a slanted guide slot 21, the purpose of which will be explained hereinafter.

At their upper ends the angle members 17 and 18 are secured to a top plate 22 which includes a platform portion 23 extending outwardly from the frame structure. This platform 23 is braced by angle members 24 which are secured as by welding near their opposite ends to the frame structure and by a diagonal brace 25 disposed between the frame and the platform 23. This platform serves to support a motor 26 that drives the conveyor through a belt 27.

Spaced downwardly from the top of plate 22 and secured to the four angle members of the frame structure is a second platform member 28 from the center of which depends a bearing member 29 in which the shaft 12 is journaled.

As best seen in Figure 2, the conveying flight comprises a series of separate units 30 secured together on the shaft 12 by means of a nut 32 disposed on an upper threaded portion 33 of the shaft 12. Each unit includes a portion of an upwardly winding trough 34 integrally formed on a length of tubing 35 equal to the pitch of the flight.

The nut 32 bears downwardly on a circular closure plate 36 which is seated on a recessed

ledge 38 on the upper end of the tube 35. The lower end of each section of tubing has a downwardly projecting rim 39 which is adapted to seat on the recessed ledge at the upper end of the section of tubing therebelow. The unit at the bottom of the conveyor differs from the other units in that, instead of a downwardly extending rim 39 at its lower end, this section has a recessed shoulder 40 against which a bottom closure plate 41 abuts.

The shaft 12 has an enlarged lower end 43 providing a shoulder 44 which is drawn up against the bottom closure plate 41 when the nut 32 is threaded downwardly on the shaft against the upper closure plate 36. Thus, the several units are rigidly held together for movement as a unit with the shaft 12. It will be noted that a loading chute 45 is suitably secured, as by welding, to the bottom unit of the conveyor while a discharge chute 46 is similarly secured to the top unit of the conveyor.

The shaft 12 which is journaled at its lower end in a bearing 47 is resiliently mounted on a coil spring 48 and is free to oscillate relative to this flight through the action of an anti-friction bearing assembly 49, which is freely disposed about the shaft 12 between the spring 48 and the bottom closure plate 41.

As previously mentioned, the helical conveying flight 11 must be given, simultaneously, a vertical reciprocating movement and an oscillating movement about its center axis. In this invention, the reciprocating movement is provided by a drive shaft 51 journaled in a pair of bearing blocks 52 on the top plate 22 and rotated through a pulley drive from the motor 26. Disposed on the drive shaft 51 directly above the vertical axis of the conveyor flight, is an eccentric 53 which has a connecting rod 54 disposed around the cam of the eccentric and associated at its lower end through a ball joint 55 with the upper end of the conveyor shaft 12. As the drive shaft 51 is rotated by the motor 26, the connecting rod will raise and lower the conveyor flight due to eccentricity of the mechanism.

It will of course, be understood that any other type of mechanism which provides a universal pivoting movement may be used in place of the ball joint 55.

The conveyor flight is oscillated about its central axis by means of a pair of rollers 58 disposed on opposite sides of the conveyor. Each roller is rotatably secured on an axle 59 which is rigidly fixed to the wall of the trough 34. The roller 58 is disposed in the slanted guide slot 21 of one of the curved plate 20 which are held between the structural angle members 17 and 18 on either side of the conveyor.

It will be readily seen therefore that, as the eccentric mechanism reciprocates the conveyor flight in a vertical direction, the slanted guide slot 21 will, through the rollers 58, cause the flight to oscillate about its center axis. The angularity of the slot determines the degree of oscillation since the conveyor flight is displaced a constant distance vertically for each rotation of the eccentric.

The angularity of the slot will also control the angle in which the material leaves the surface of the conveyor flight. Referring to Figure 1, it is clearly seen that the path of travel of the roller 58 in the slot 21 is, in this illustration, at approximately 45° to the horizontal, while the angle of climb of the conveyor flight is approximately 8°. Thus, the material will leave the sur-

face of the flight at an angle of approximately 37° to the surface of the flight.

As many rollers 58 and guide slots 21 may be used as is dictated by the height of the conveyor assembly.

In cases where a heavy material is being conveyed in the conveyor of Figure 1 and considerable amounts of power is being exerted by the eccentric drive means, vibrations will be set up in the support structure. In such a case it may be desirable to provide for counterbalancing the vertical movement of the spiral flight in order that the vibrations will not become excessive. In Figure 5, one means of counterbalancing this installation is shown.

In this modification a weight 62 is adjustably mounted on a shaft 63 which is driven from an eccentric 64 keyed to the drive shaft 51. The bearing block 52 may be extended upwardly to provide a standard for pivotally supporting a lever 65 attached pivotally to the rod on which the weight 62 is mounted. The pair of eccentrics on the drive shaft are oppositely disposed so that when the conveyor is moved downwardly the weight 62 is moved upwardly. Thus vibrations and shocks are counteracted and not transmitted to the frame structure. It is to be understood that the weight 62 must equal the weight of the conveyor or the throw of the eccentric 64 must be made several times as great as that of the eccentric 53.

It will, of course, be obvious that the spring 48 may be eliminated from the conveyor of Figure 1. In this case the weight of the entire conveyor flight will rest on the thrust bearing 47. The principle of operation will, however, remain the same.

Rotation of the conveyor flight about its center axis may be obtained by means other than the roller 58 and slot 21 previously mentioned. In Figure 6 a second mechanism for rotating the conveyor flight is illustrated.

The spiral flight 68 of this modification may be constructed of several individual units as in the spiral 11 of Figure 1. The flight may conveniently be held between a platform 69 and the top closure plate 36 by means of the nut 32 threaded on the shaft 12, which in this case has a lower shoulder 70 disposed under the platform 69. By clamping the several units of the spiral flight between the nut 32 and the shoulder 70, the spiral will be suitably held against the bottom platform 69 to assure oscillation of the flight with the platform 69.

To impart a vertical reciprocating movement to the conveyor, there is provided a drive shaft 72 journaled in bearings 73 and 74 secured in an upright position on a circular platform 75. This platform 75 is connected to the platform 69 in substantially parallel spaced relation by four angle members 77 which may be welded at either end to the platforms.

A stub shaft 79 is welded at its upper end in an opening in the platform 75 directly below and in alignment with the shaft 12 and projects downwardly into a bearing assembly 81 secured to a suitable base member 82 by the bolts 83. A plate 85 having a central opening through which the shaft 79 passes is held spaced above the base 82 by a plurality of bolts 86 and spacer sleeves 87.

A coil spring 88 is disposed about the shaft 79 with its lower end resting freely on the plate 85 and its upper end abutting a disk 90. This disk is separated from the platform 75 by an anti-friction bearing assembly 91. With this arrange-

ment the platform 75 is free to oscillate about the shaft 79 without causing rotation of the spring 88.

Near the center of the shaft 72, a pulley 93 is keyed thereto, the pulley being connected through a belt 94 to a suitable source of power, such as the motor 26, Figure 1. A weight 95 is secured near either end of the shaft 72 at points equidistant from the pulley 93. As the pulley is rotated by the external drive means, the weights 95 will cause reaction forces to be set up in the structure tending to move the structure sidewise and up and down in a vertical direction. Since the shafts 12 and 79 are journaled in upper and lower bearings, the conveyor will be unable to move sidewise and only a vertical reciprocating movement of the spiral flight will result.

To impart oscillating movement to the embodiment of this invention disclosed in Figure 6, there is provided a pair of arms 97 and 98 which are pivotally mounted at their lower ends in bearing blocks 99 secured to the base 82. At the upper end, the arms 97 and 98 are pivotally connected to ears 100 depending in diametrically opposed positions from the lower surface of the platform 75. It will immediately be recognized that, as the spiral flight 68 is reciprocated in a vertical direction by the action of the weights 95, the up and downward swinging movement of the arms 97 and 98 will cause the platform 75 and consequently the spiral flight 68 to oscillate about the shafts 12 and 79.

The angle at which the material carried on the surface of the spiral flight is thrown upwardly will depend upon the position and length of the arms 97 and 98, since the material will be thrown in a direction substantially tangential to the arc described by the outer end of the arms.

As the platform 69 oscillates, the upper ends of the arms 97 and 98, which are fastened thereto, will of course tend to oscillate with the point of the platform to which they are attached. Since the arms 97 and 98 are rigid, means must be provided to allow them to pivot in their mountings. To accomplish this we have provided a rubber mounting for the upper and lower end of these arms. As seen in Figure 11, a rubber sleeve 102 is molded between an inner sleeve 103 and an outer sleeve 104. The inner sleeve 103 is held rigid between the bearing blocks 99 by a bolt 105 which passes therethrough. The outer sleeve 104 is pressed into the hub of the arm 97. Thus, since the sleeves 103 and 104 are held in fixed position, pivoting of the arm in the mounting will be accomplished by flexing of the rubber sleeve 102.

For the purpose of varying the frequency of the spring mounting, a plurality of coil springs 106 may be secured, as by eyelets 106a between the platform 75 and the base plate 85. Since these springs are secured spaced from the axis of the conveyor they will also have a stabilizing effect.

The upper end of the arm also has a rubber sleeve held between inner and outer sleeve to permit pivoting of the arm at this point.

As shown in Figure 6, the arms 97 and 98 extend upwardly through an opening 101 provided at one side of the plate 85.

There is thus illustrated in Figure 6 a spiral conveyor mounted on coil springs and arranged to be simultaneously reciprocated in a vertical direction and oscillated about its center axis.

If the coil springs are eliminated from this assembly the weight of the conveyor will rest

solely on the bearing 81. However, the conveyor will be operated in the same manner as above described.

In order that the slow frequency spring 48 of Figure 1 be used to support as much of the weight of the conveyor as possible it may be desirable to incorporate in the conveyor drive mechanism means for allowing the conveyor to sink or assume a floating position on the spring mounting in accordance with variations in the weight of the loaded or unloaded conveyor.

In Figure 7 such a mechanism is illustrated. It comprises a cylinder 110 mounted on a shaft 112 around which the conveyor flight is assembled. A piston 113 is secured to the lower end of the drive shaft 12, which is disposed for reciprocating in a fluid tight seal 114 in the cylinder 110. The cylinder 110 is filled with a fluid, preferably a liquid such as oil, on both sides of the piston 113. A bypass port 115 in the piston 113 affords communication between both sides of the piston.

Since the cylinder 110 is connected directly to the spring-mounted flight 68, the flight will be allowed to sink on the spring mounting until substantially the entire static load of the conveyor is carried thereby. When the shaft 12 is reciprocated by the drive means the fluid drive mechanism will act as a rigid link for reciprocating the conveyor. Thus, the spring mounting will automatically adjust its position for changes in the total weight of the conveyor due to loading or unloading.

In the arrangement shown in Figure 7, a modified spring mounting and centering member is illustrated. This member comprises a leaf spring 107 which is welded as at 108, to the frame member 17 and has a bearing 109 secured to one end for receiving the shaft 112 which passes freely therethrough. Collars 111 are keyed to the shaft 112 above and below the bearing. Thus, the shaft is free to rotate relative to the shaft but must vibrate vertically with the bearing and the leaf spring.

The fluid cylinder 110 is adapted for use with the conveyor of Figure 1, with either the roller and slot rotating mechanism or with the swinging arms of Figure 6.

Figures 8 and 9 illustrate a third form of means for causing rotative movement of the conveyor. This mechanism comprises a plurality of individual spiral units clamped between an upper disk 36, Figure 2, and a platform 116 by the nut 32 threaded on the upper end of the rod 12. This rod passes through a central aperture in the disk 36 and, at its lower end, through a central aperture in the closed end 117 of a sleeve 118, Figure 9. A nut 119 threaded on the lower end of the rod 12 coacts with the nut 32 to clamp the units together. The sleeve 118, at its lower end, is secured as by welding to the platform 116 and has an opening 120 near its upper end through which the nut 119 may be adjusted.

Thus, the tighter the nut 119 is drawn on the rod 12, the tighter the sleeve will be pressed against the platform 116.

Vertical reciprocation of this structure is obtained through a lever 123 which is pivoted in a fulcrum 124 and arranged, at one end, to be moved up and down by an eccentric mechanism driven from a drive means 125, such as the electric motor 26 of Figure 1. At its other end the lever 123 is pivotally connected to a push rod 126 which extends upwardly inside the sleeve 118 for connection at its upper end to a piston 127 slidably mounted in a cylinder 128. Fluid tight packing is disposed around the rod 126 where it

enters the cylinder 128. The cylinder 128 is supported by a rod 130 and a ball joint 131 from a disk 132 which is welded across the inside of the sleeve 118. The up and down movement of the outer end of the lever 123 is transmitted to the sleeve 118 and therefore to the spiral flight through the fluid cylinder 128.

In Figure 9 it will be seen that a restricted passage 133 is drilled through the piston 127 establishing communication between the fluid on either side of the piston. Thus, the fluid cylinder 128 will act in the same manner as the cylinder 110 of Figure 7 to permit the conveyor to float on the spring mounting.

15 In this form there is provided a plurality of arms 134 which may suitably be made from rods of spring steel. These rods may have various cross-sections but are preferably of round cross-section. In all forms the mass of the rod is uniformly distributed on all sides of a central axis so that the rod has the characteristic of being able to flex universally and uniformly in any direction from the axis. Each arm 134 is 20 adjustably held at its lower end in a block 135 by means of a set screw 136. The block 135 is secured by bolts 138 and 139 to a suitable base 140, the bolt 139 being disposed in a horizontal arcuate slot (not shown) in the base flange portion of the block for permitting the block to be 25 adjusted by pivoting about the bolt 138 as center. Near its upper end, each rod passes through a 30 segmental circular cutout portion 144, Figure 8, in the platform 116. A block 145 is adjustably secured to each arm by set screws 146 and has a slanted brace 147 pivotally secured by a cap-screw 148, Figure 8, to the platform 116.

Thus, each rod is mounted so that its effective length can be increased or decreased to regulate the frequency of the spring arms 134. The 40 pivotal mounting of the block 135 and 145 permits this adjustment without deformation of the spring arms 134.

As the spiral flight is reciprocated in a vertical direction, the spring arms 134 will oscillate the flight in the same manner as the arms 97 and 98 45 of Figure 6 or the slot 21 of Figure 1.

Sets of spring arms 134 can of course be connected to the conveyor flight at various elevations by mounting them on a support platform built around the conveyor at an appropriate 50 height. The platform on which the blocks 145 are mounted could be readily secured to a cylindrical sleeve fastened to the periphery of the flight.

It is evident that as many sets of spring arms 55 may be used on a spiral conveyor as is necessary to keep the conveyor centered at all times.

From the above description it will be readily seen that the several spring arms act to center the spiral flight about an imaginary central axis. 60 Thus, no center bearings are needed with this construction.

It is within the scope of this invention to provide a conveyor having a set of spring arms 134 as the lower center bearing and having a typical center bearing, such as bearing 29 of Figure 1, as the upper center bearing. Or, the spring arms may replace both the upper and lower center bearings, using one or more sets of spring arms depending upon the height of the conveyor.

Although in the illustrations of this application we have shown five spring arms mounted equi-distantly about the conveyor, it is within the scope of this invention to use any number of spring arms for the purpose of centering the con-

veyor, resiliently mounting the conveyor and imparting oscillating movement thereto.

The spring mountings and drive means of this invention are also applicable to a trough conveyor. In Figure 10 a trough 150 is mounted substantially horizontally on spring rods 151 which are adjustably secured in blocks 152 and 153 on both sides of the trough. A motor 154 operates an eccentric 155 to reciprocate the trough in a substantially horizontal direction through a piston 156 slidably mounted in a fluid cylinder 157. A passage 159 establishes communication between both sides of the piston. The cylinder is secured through a ball joint 158 to the conveyor. Horizontal reciprocation of the conveyor will result in the movement of the conveyor at an angle upwardly to the left as seen in Figure 10 for discharge through a chute 160 secured in an opening in the bottom of the conveyor.

The trough conveyor illustrated in Figure 10 is adapted to move material along its surface from right to left according to the directional throw method of conveying. The angle at which the material leaves the surface of the conveyor will depend upon the location of the arms and their length.

It will be understood that the fluid cylinder 157 permits the trough conveyor to float on the spring rods 151 in the manner described in connection with the cylinder 110 of Figure 7. This type of floating drive may of course be replaced by a single, rigid drive shaft, in cases where it is not desired to take full advantage of the spring mounting.

Further, the spring arms 151 may be advantageously replaced by one or more leaf springs secured between the supporting base and the central section of the bottom panel of the trough.

Reciprocation of the trough may of course be effected by means of rotating weights secured to the trough and operating in substantially the same manner as the weights 95 of Figure 6. In this case, the weights would be arranged to augment each other in a horizontal direction to cause reciprocation of the trough but to counterbalance each other in a vertical direction. Thus, the weights would have to be rotated in opposite direction by any of the well known mechanical arrangements, such as by gears.

Heretofore this disclosure has been concerned with conveyors mounted on slow frequency springs. As previously stated an important feature of this invention is the provision of means for operating the conveyor within the natural frequency range of the spring mounting.

The natural frequency of a spring mounting under a load mounted directly on the springs without externally connected dampening members may be computed from the equation

$$N = \frac{187.7}{\sqrt{d}}$$

where N equals the frequency in R. P. M. and d equals the deflection under the load in a vertical direction.

If externally connected members such as the arms 97 and 98 of Figure 6 or the roller and slot arrangement of Figure 1 modify the vertical movement of the load, the natural frequency of the spring mounting will be affected. In the case of the slot of Figure 1 disposed at 45° angle the natural frequency is damped to one half the computed frequency.

Each of the spring mountings described in con-

nnection with Figures 1, 6, 8 and 10 may be adapted for operation for conveying at the natural frequency of the spring. However, in all cases the conveyor must be permitted to settle to its normal floating position even while load is increased or decreased. Thus, a fluid cylinder such as cylinder 110 of Figure 7 must be incorporated in the drive mechanism. Or the loaded conveyor must be permitted to settle on the springs before a suitably adjusted drive arm is connected thereto.

While the natural frequency of a spring mounting may be calculated from the above-mentioned formula, it must be remembered that the relation of the drive mechanism and the conveyor is such that they will operate in resonance in a range which extends approximately 5% above and below the calculated value. Thus, if the calculated or mean value of the natural frequency is 285 vibrations per minute, the range of resonance will extend approximately from 270 to 300 vibrations per minute.

Therefore, it is to be understood that herein-after when the "natural frequency range" of a spring mounting is referred to, it means the range in which the drive means and the conveyor are in resonance.

Rate of conveying material in the conveyor depends upon the speed and the amplitude of the conveyor vibrations. If a liquid, such as oil, is used in the drive cylinder 110, the speed of natural frequency of the spring mounting must be predetermined to be within the range of speed that will give the desired conveying rate. The amplitude of the vibration will, of course, depend upon the throw of the eccentric. Thus, for each installation using liquid in the cylinder 110, a definite speed and amplitude is predetermined to give the necessary discharge.

The rate of conveying may be varied in any frequency range by manually adjusting the amplitude of the conveying stroke. In Figure 12 a hydraulic drive mechanism is illustrated connected between the eccentric drive means 125 and the push rod 126.

This hydraulic drive comprises a pair of fluid cylinders 170 and 171 mounted on a support 172. The cylinder 170 has a piston 173 mounted for reciprocation therein and connected to a drive arm 175 leading from the eccentric 125. The cylinder 171 has a piston 177 connected to the rod 126 leading to the fluid cylinder 128. The space above the piston in cylinder 170 is connected through a flexible tube 179 to the space above the piston in cylinder 171. Likewise, the spaces below the piston are interconnected by a flexible tube 180. This fluid system is designed to run full and consequently reciprocating movement of the piston 173 causes reciprocating movement of the piston 177 and therefore movement of the conveyor. A bypass line 182, having a hand operated valve 183, is connected between the tubes 179 and 180. The amount of the valve 183 is opened will of course determine the length of stroke of the rod 126.

Thus, the conveying rate may be varied with the drive means operating at constant speed.

In Figure 13 a modification of the drive means of Figure 12 is disclosed. In this modification, the piston 177 is secured to a rod 185 fastened to a support member 186. The cylinder 171 is secured to the base 116 of the conveyor. Thus, the piston 177 is held stationary while the cylinder 171 and the conveyor is moved.

This modification permits the conveyor to be mounted close to the ground.

11

A control bypass valve, such as valve 183, may of course be installed in the apparatus of Figure 13.

A second method of obtaining a variation in the speed of conveying is by use of a drive cylinder, such as the cylinder 110, using air as the driving fluid. Referring to Figures 8 and 9, with a predetermined length of stroke of the rod 126 and using air in the cylinder 128, the rate of conveying of material can be varied by varying the speed at which the rod 126 is reciprocated, which variation may be made by any manually operated speed changer connected to the drive shaft of the motor. As the reciprocated speed of the rod is increased, the effective stroke of the conveyor will be raised so that the stroke of the conveyor will be greater than the stroke of the rod 126. This increase of stroke results in an increase in amplitude and consequently an increase in conveying speed.

If the speed is decreased, the stroke of the conveyor will be decreased to a point where it is less than the stroke of the rod 126. This variation of the effective length of the conveyor stroke in spite of the fixed stroke of the rod 126 is a result of the inherent characteristics of the air cylinder and results in controlling the conveying speed with a fixed stroke by varying the reciprocations.

Thus, by the use of an air cylinder the rate of conveying may be varied from a trickle of material to a rapid rate.

In summation, there is disclosed in this invention, a spiral conveyor and a trough conveyor and various means for operating each conveyor without spring support, with slow frequency spring mounting and with a natural frequency spring mounting.

There is further disclosed means for permitting the conveyor to settle or float on the spring mounting with changes in load conditions.

The conveyor apparatus herein disclosed, and especially the natural frequency conveyors, have many advantages both as to economical construction and efficient operation heretofore unknown in the conveyor field.

We have heretofore described various modifications of our invention, but it will be understood that numerous other variations may be made in the character, construction and arrangement of the component parts and in the general assembly, without departing from the principles and scope of the invention. It is, therefore, not the purpose to limit the patent granted hereon otherwise than necessitated by the scope of the appended claims.

We claim as our invention:

1. In a mechanism of the character described, the combination of a vibratory material handling structure, resilient means supporting said structure and which permit said structure to settle under load, means extending between said structure and a base with respect to which said structure vibrates, said last named means comprising a vibrator and a coupling, through which the vibrations from said vibrator are transmitted to said structure, which coupling is deformable to compensate for changes in the distance between said structure and said base, as the former settles under load, said coupling being thus deformable at a rate of movement which is substantially less than the rate of movement imparted to said structure by said vibrator at the normally used frequency and amplitude thereof.

12

2. The mechanism according to claim 1 characterized further in that said coupling, when deformed, retains no strain as a result of being thus deformed.

5 3. The mechanism according to claim 1 characterized further in that said coupling comprises relatively movable members forming a chamber containing substantially incompressible liquid, and bleed means permitting discharge of liquid 10 from such chamber for enabling settling of said structure, but at a reduced rate as aforesaid so that substantially positive driving of said structure is effected through said members and the liquid-containing chamber defined thereby.

15 4. The mechanism according to claim 1 characterized further in that said coupling comprises a double-acting piston-cylinder assembly defining a pair of chambers containing substantially incompressible liquid and having restricted communication with each other at a rate such that 20 substantially positive driving of said structure by said vibrator is effected through said coupling while such restricted communication between said chambers enables a settling of said structure under load at the reduced rate aforesaid.

25 5. The mechanism according to claim 1 characterized further in that said coupling comprises a piston-cylinder type hydraulic shock absorber in which bleed means between bodies of substantially incompressible liquid therein permits settling of said structure but prevents perceptible relative piston-cylinder movement at the frequency of vibration of said structure by said vibrator.

30 6. The mechanism according to claim 1 characterized further in that said vibrator is fixedly mounted, and that said coupling is connected between said vibrator and said structure.

35 7. The mechanism according to claim 1 characterized further in that said coupling comprises a double-acting piston-cylinder assembly defining a pair of chambers containing substantially incompressible liquid and having restricted communication with each other at a rate such that 40 substantially positive driving of said structure by said vibrator is effected through said coupling while such restricted communication between said chambers enables settling of said structure under load at the reduced rate aforesaid, and a bypass valve between such chambers whereby, 45 upon opening of said valve, said members, and thus said vibrator and structure, may vibrate independently of one another as during starting and stopping thereof.
